UNITED STATES PATENT OFFICE.

HENRY HILL, OF HALIFAX, NOVA SCOTIA, CANADA.

EXTENSIBLE STEPLADDER.

Application filed February 18, 1927. Serial No. 169,329.

The present invention pertains to a novel step ladder adapted for use in the ordinary manner and also constructed so that the main and prop sections thereof may be brought into alignment to form a single ladder by which higher levels may be reached.

The principal object of the invention is indicated in the foregoing statement and involves further a device of this character constructed in a simple manner.

With this object in view, the prop rails of the construction are provided with rungs so that the user may climb these rungs when the ladder is extended. The invention includes also a spring device carried by the main section and adapted to act on the prop section in order to aid in bringing the latter into alignment with the main section. Further, the invention comprises, in combination with the step ladder braces, a pair of springs acting on the pivot ends of the braces in such a manner as to secure them in operative position and also to assist in raising them when the ladder is to be extended.

The invention is fully disclosed in the following description and in the accompanying drawings in which:

Figure 1 is a side elevation of the ladder in extended form;

Figure 2 is a detail vertical section in a plane parallel to that of Figure 1;

Figure 3 is an elevation of the ladder arranged as a step ladder;

Figure 4 is a detail vertical section showing the brace and associated parts;

Figure 5 is a side elevation of the device erected as a step ladder; and

Figure 6 is a similar view of the device positioned for use as a short ladder propped against a wall.

Reference to these views will now be made by use of like characters which are employed to designate corresponding parts throughout.

It will be apparent after a comparison of Figures 1 and 5 that the device of the invention may be used as a step ladder and also as a single ladder to be propped against a wall.

With reference to the step ladder assembly, the ladder part used in this adjustment comprises a pair of parallel rails 1 which are joined and spaced preferably by rungs 2 arranged in pairs. The ordinary flat steps may be used instead of the rungs, but such rungs are preferable in order that the same form tread may be used throughout.

The prop section in the step ladder assem-

bly comprises a pair of rails 3 pivoted as at 4 to the inner faces of the rails 1. In line with the rails 3, spring strips 5 of the jack-knife principle are secured to the inner faces of the members 1. These strips 5 may be formed of spring metal or other suitable material and arranged so that the upper ends are disconnected for edgewise movement for resilient engagement with the rectangular pivot extension of the rails 3. The pivoted ends of the member 3 are notched as at 6 to receive the upper ends of the spring members 5. Finally the springs are concealed by additional strips 8 secured to the members 1 by the pivot pins 4 of the rails 3.

Over the top of the rails 1 is laid a top step 9 in the usual manner of step ladder construction. The rails 3 are joined together and held in spaced relation by rungs 10 secured between them. The peculiar relation between the notches 6 and the upper ends of the springs 5 permit the prop rails 3 to be swung upwardly and into alignment with the rails 1 whereby a single ladder is formed as shown in Figure 1. Thus, uniform rungs such as the members 2 and 10 may be used throughout the construction.

A further feature of the invention resides in the braces for securing the device in the position of an ordinary step ladder. These braces are designated in Figures 4 and 5 by the numeral 11. They are pivoted at one end to the inner faces of the member 8 as indicated by the numeral 12, while the remaining end of each member 11 has a slot 13 adapted to receive the opposite rung 10 between the members 3. The pivoted end of each member 12 is engaged by a flat spring 14 also secured to the inner face of the adjacent member 8 by means of pins 15. When the props are in use as in Figure 5, the pivoted extremities 16 thereof are engaged by the springs 14 whereby the props are prevented from slipping off the rungs 10. Also, when these props are lifted from the rungs 10, the springs 14 act on the sides 17 thereof and raise the members to the position shown in Figure 4.

A similar action occurs when the rails 3 are raised to extend the ladder. The action of the springs 5 in the notches 6 aids in the upward travel of the prop section and further holds the two sections in alignment.

While a specific embodiment of the invention has been illustrated and described, it is to be understood that various alterations in the details of construction may be made without

departing from the spirit of the invention as indicated by the appended claims.

Having thus fully described the invention, what I claim as new and desire to protect by

5. Letters Patent is:

1. An extensible step ladder comprising main ladder rails, treads between said rails, prop rails pivoted to the upper ends of said main rails and adapted for alinement there-

10 with, rungs provided between said prop rails, notches formed in the pivoted ends of said prop rails, and spring members carried by said main rails and adapted for reception in said notches in order to hold both sets of rails in alinement.

15 2. An extensible step ladder comprising a main ladder section including a pair of longitudinal side rails, treads mounted transversely between the said rails, a prop section includ-

ing a pair of side rails, treads mounted in 20 transverse position between the side rails, one end of each prop section side rail being formed with a reduced pivot extension of non-circular form, means for pivotally connecting the said reduced ends of the prop section side 25 rails with the upper end of the main section, and a pair of spring strips secured to the inner sides of the main section side rails at the upper end portion and extending parallel with the side rails, the upper ends of the strips 30 being arranged to resiliently engage the reduced pivot extensions of the prop section side rails so as to resiliently support the prop section when the same is arranged in co-extensive alignment with the main section. 35

In witness whereof I have hereunto set my hand.

HENRY HILL.
